UNITED STATES PATENT OFFICE.

ARTHUR RICHARD CARTER, OF HAMMOND, LOUISIANA.

STEAM-ENGINE.

1,181,110.

Specification of Letters Patent.

Patented May 2, 1916.

Application filed August 9, 1915. Serial No. 44,563.

To all whom it may concern:

Be it known that I, ARTHUR R. CARTER, a citizen of the United States, and a resident of Hammond, in the parish of Tangipahoa and State of Louisiana, have invented certain new and useful Improvements in Steam-Engines, of which the following is a specification.

My invention is an improvement in the class or type of multiple-piston steam-engines, and the objects are to simplify the construction and reduce the cost, weight, and friction of the parts connected with the pistons and crank shaft, as well as to minimize friction and vibration.

The details of construction, arrangement, and operation of parts are as hereinafter described and illustrated in the accompanying drawings, in which:—

Figure 1 is mainly a horizontal longitudinal section of my improved engine; Fig. 2 is a cross section on the line 2—2 of Fig. 1; Fig. 3 is a similar section on the line 3—3; and Fig. 4 is a cross section on the line 4—4; Fig. 5 is a vertical longitudinal section of the engine illustrating certain details.

In Fig. 1, the numeral 1 indicates a double crank-shaft, 2 the long cylinder having a steam-chest 2^a, and 3—3^a indicate a pair of pistons, or follow-heads, connected by rods 4, while numerals 5—5^a indicate another set of pistons or follow-heads connected by the solid piston rod 6.

The piston 3 is mounted on a relatively short, hollow shaft 7, through which the solid rod 6 is adapted to slide, and is itself slidable in the head of the cylinder 2. The long piston rod 6 is connected with the crank-shaft 1 by a rod or pitman 8, and the short, hollow, piston rod 7 is similarly connected with the crank by a rod 9. The two piston rods 6 and 7 are respectively provided with crossheads 10 and 11, both of which slide in one and the same guide 12. Thus the number and weight of the parts usually constituting this portion of engines of this type are greatly reduced.

As shown in Fig. 1, the rods connecting the pistons, or follow-heads, 3—3^a slide through the piston 5^a, and, in turn, the solid piston-rod 6 slides through the pistons 3 and 3^a, suitable stuffing-boxes being provided in the respective cases.

A slide valve 13 of the ordinary D-type is arranged in the steam-chest, 2^a, to govern

inlet and exhaust of steam, and the same is connected with an eccentric 14, on the crank-shaft 1, by means of rods 15, 15^a, and a crosshead 16 working in the fixed guide 17. The rod 15^a is necessarily jointed to the crosshead, as shown. The position of the slide valve 13 in Fig. 1 is such that steam is exhausted through the three ports 18, there being one port adjacent to each cylinder-head and another midlength of the cylinder, all the said ports being connected with the chamber 18^a of the valve, which in turn communicates with exhaust pipe 19, (see Figs. 2 and 5). Simultaneously with the exhaust, steam is being admitted from steam-chest 2^a through ports 20, which are indicated by dotted lines in Fig. 1, into the spaces 21 between the pairs of pistons 3, 5 and 3^a, 5^a, so that the pistons 3 and 5^a are caused to approach each other, while the pistons 3^a and 5 move toward the respective cylinder heads. Thus the power applied to pistons 3 and 3^a is transmitted by rods 4 and hollow piston-rod 7 to cross-head 11, and thence through connecting-rod 9 to an arm of the crank-shaft 1; at the same time, the steam pressure or power applied to pistons 3 and 3^a, in opposite directions, is transmitted through the long, solid rod 6 to crosshead 10, and thence, by connecting rod 8, to the crank shaft 1. Thus, the shaft being rotated, the eccentric 14 reciprocates the slide valve 13 so that it alternately opens and closes the steam ports and effects the operation of the engine, as will be readily understood without further description. In this manner I work steam in five different compartments of the cylinder during each revolution of the crank shaft.

I claim:

1. The combination, with an engine cylinder having steam ports located at its ends and intermediately, and four pistons which are slidable in the cylinder and adapted to receive steam between the members of each pair, of solid and hollow rods connected with such pistons, two crossheads with which the piston rods are in turn connected, a single guide which serves for both crossheads, and a double crank-shaft, and rods connecting the cranks with the crossheads as described.

2. The improved steam-engine of the type indicated, the same comprising the cylinder having steam ports at its midlength and ends, and also at two points intermediate

the midlength and ends, two pairs of pistons, or follow-heads which are rigidly connected and slideable in opposite directions, alternately, as steam is admitted or exhausted between the members of each pair and the cylinder heads, one pair of said pistons having a relatively short hollow rod and the other pair of pistons having a long, solid rod which is slideable in the hollow one,

two crossheads with which the pairs of piston-rods are respectively connected, a single guide which serves for both cross-heads, and rods connecting the latter with the double crank-shaft, as described.

ARTHUR RICHARD CARTER.
